UNITED STATES PATENT OFFICE.

HU M. HARRIS, OF CHATTANOOGA, TENNESSEE, ASSIGNOR TO LUCEY MANUFACTURING CORPORATION OF TENNESSEE, OF CHATTANOOGA, TENNESSEE, A CORPORATION OF TENNESSEE.

ENGINE.

Application filed November 10, 1925. Serial No. 68,069.

The invention relates in general to stationary engines but more particularly to engines for oil well drilling outfits.

Special requirements for engines of the latter class are that they shall be simple, sturdy and dependable and that they require but little attention, be compact, occupy but small space for the power provided and be readily accessible for quick repairs.

Further desirable features are to have a lowered center of gravity and to have a well balanced, quiet running mechanism.

The foregoing and other desirable objects are attained in this invention by a novel form of valve gear involving a reverse link mounted stationary on the bed of the engine, and an upstanding radius link shiftably fulcrumed at its lower end in said reverse link and carrying at its upper end an eccentric rod connected through bellcrank linkage with the slide valve of the engine.

The above and other novel features of the invention are set forth in the following specification and described by reference to the drawings accompanying and forming part of the same.

The drawings illustrate an actual commercial embodiment of the invention, but it should be understood that the structure may be modified in various respects without departure from the spirit and scope of the invention as hereinafter defined and broadly claimed.

Figure 1 is a side elevation of a form of the invention incorporated in a well drilling engine.

Figure 2 is a broken plan view of the same indicating the engine as of the twin cylinder type, with one cylinder only shown.

Figure 3 is a detached perspective view of the valve gear.

In the present disclosure, the cylinder 5 of the engine is supported at one end of the web or frame 6 rising from the bed plate 7 and the crank shaft 8 is journaled at 9 at the opposite end of said upright framing. The intermediate portion of this framing carries the guides 10 for the cross head 11 which is connected with the piston rod 12 and carries 50 the connecting rod 13 engaging the main crank 14.

The valve gear is mounted on the engine bed at a low level, below the center line of the engine and comprises an upstanding

slotted reverse link 15 fixedly secured on the base by bolts 16, and an upstanding radius link 17 having its lower end swiveled in the reverse link and its upper end serving as a fulcrum for the eccentric rod 18. This eccentric rod derives its motion from an eccentric pin 19 carried by an eccentric crank 20 secured at 21 on the main crank 14.

The upper end of the radius link 17 is shown as forked at 22 to embrace the eccentric rod and carry the fulcrum 23 therefor. The lower end of this link is shown as forked at 24 to embrace the reverse link and receive the roller or block 25 fitting in the slot of the reverse link. Extending through the arms of the fork 24 and the interposed roller 25 is a bolt 26 and on the outer ends of this bolt are engaged the arms of a fork 27 on the end of the reach rod 28. The other end of this reach rod is pivoted at 29 to a reversing arm 30 on the rock shaft 31, which latter can be operated by a reverse lever 32.

From the rear end of the eccentric rod 18, motion is transmitted to the slide valve of the engine by a transmission link 33 having its upper end forked at 34 to embrace the rearward end of the eccentric rod and carry the pivot bolt 35 therefor, the lower end of such transmission link being forked at 36 to embrace the forked ends of the reach rod 37 and radius link and being pivoted at 38 to the forwardly extending arms 38 of a bellcrank element having an upstanding arm 39 pivoted at 40 to the slide valve rod 41. The shaft 42 which carries the bellcrank arms 38, 39 and the reverse lever shaft 31 are both shown journaled in the upstanding flange or web 6 of the base.

The position of the reverse lever indicated in the several views is the forward running position of the engine, the radius link 17 being supported from the rear end of the slot in the reverse link so that the upper end of said radius link is oscillated by the eccentric rod 18 through the arc indicated starting from the center 35 in Figure 1. The eccentric rod is thus supported on a rocking fulcrum 23 and the end of the rod in rear of such fulcrum imparts a raising and lowering movement to the transmission link, causing that to rock the bellcrank 38, 39 which is connected with the valve rod 41. Reversal of the engine is effected by

simply swinging the reverse lever 32 to the left in Figure 1 so as to carry the support for the lower end of the radius link into the forward end of the slot in the reverse link 5 15. In that position the fulcrum for the eccentric rod will describe the other or reverse arc indicated in Figure 1. Reversal may be effected without shutting off steam as the lower end of the radius link passes first 10 through a neutral position midlength of the slot where the movement imparted to the valve is insufficient to effect rotation of the engine in either direction so that the change-over from one direction to another is effected 15 gradually and without jar.

The movements of the valve operating parts are relatively slow and of comparatively slight extent and as all these parts are at a low gravity center, the action is 20 particularly quiet and well balanced. The mechanism is particularly compact and close coupled because of the fact that the reach rod is forked to straddle the radius link and reverse link and the transmission link is 25 forked to straddle all of these parts so that viewed from the side as in Figure 1, the lower ends of all these parts and including the lower end of the valve actuating bell-crank all stand in a common plane. All 30 parts also are readily accessible, easily taken care of and if necessary, readily removed for repair purposes or the like.

To enable close adjustment in setting the valve, the bolts 16 which secure the reverse 35 link in place are shown as stay bolts against which impinge adjusting screws 45 extended inward from the ends of the link. The link is shown longitudinally slotted at 46 for the stay bolts, lock nuts are indicated at 47 40 for securing the positioning screws in their finally adjusted relation and clamp nuts are indicated at 48 on the upper ends of the stay bolts for fixing the link in the position to which it has been shifted.

45 The supporting of the radius link from below and the suspending of the transmission link from the rear end of the eccentric rod are particularly advantageous features, keeping down the height of the valve gear to be- 50 low the level of the cross head guides, with substantially all parts below the longitudinal center of the engine, tending to steady and quiet the operation of the engine.

In view of the fact that the present in- 55 vention may be adapted to engines for many different purposes and may be changed in its structure to meet various requirements, the specification and claims are to be interpreted broadly, the terms employed being 60 used in a descriptive rather than in a limit- ing sense, except possibly for such limita- tions as may be imposed by the state of the prior art.

What is claimed is:

65 1. A stationary steam engine of the hori-

zontal type comprising an engine bed, a cylinder mounted upon the bed at one end, a crank shaft journaled at the opposite end of the bed, cross head guides upon the bed between the cylinder at one end and the 70 crank shaft at the opposite end, a valve actuating rock shaft journaled on the bed below the cylinder and beneath the cross head guides, a valve actuating rocker arm projecting upwardly from said rock shaft and an operating arm projecting laterally from said rock shaft away from the cylinder, a reversing shaft journaled on the bed plate in front of the rock shaft, a slotted reverse link mounted on the bed and between the rock 75 shaft and reversing shaft with the concave side of the slot therein faced upwardly, an auxiliary crank fixed on the main crank, an auxiliary connecting rod engaged at one end with said auxiliary crank, a radius link having its lower end shiftably pivoted in the slot of the reverse link and carrying at its upper end a fulcrum for the auxiliary connecting rod, a connecting link suspended from the auxiliary connecting rod and having its upper end pivoted to the end of said connecting rod at a point beyond the fulcrum of said rod and its lower end pivotally engaged with the laterally extending arm of the rock 85 shaft, an upwardly projecting arm on the reverse shaft, a reach link extending from said upwardly projecting arm over the reverse link and connected with the shiftable pivotal support for the lower end of the radius link and an operating lever extending 90 upwardly from said reverse shaft.

2. A steam engine of the horizontal type comprising engine bed, a cylinder mounted on the bed at one end, a crank shaft journaled at the opposite end of the bed, cross head guides on the bed between the cylinder at one end and the crank shaft at the opposite end, a valve actuating rock shaft journaled on the bed below the cylinder and cross head guides, a valve actuating rocker arm projecting upwardly from said rock shaft and an operating arm projecting laterally from said rock shaft away from the cylinder, a reversing shaft journaled on the bed plate in front of the rock shaft, a slotted reverse link mounted on the bed plate and between the rock shaft and reversing shaft with the concave side of the slot therein faced upwardly, an auxiliary crank fixed on the main crank, an auxiliary connecting rod engaged at one end with said auxiliary crank, a radius link having its lower end shiftably pivoted in the slot of the reverse link and carrying at its upper end a fulcrum for the auxiliary connecting rod, a connecting link suspended from the auxiliary connecting rod and having its upper end pivoted to the end of said connecting rod at a point beyond the fulcrum of said rod and its lower end pivotally engaged with the laterally extending arm of the rock shaft, an upwardly projecting arm on the reverse shaft, a reach link extending from said upwardly projecting arm over the reverse link and connected with the shiftable pivotal support for the lower end of the radius link and an operating lever extending 100 upwardly from said reverse shaft.

3. A steam engine of the horizontal type comprising engine bed, a cylinder mounted on the bed at one end, a crank shaft journaled at the opposite end of the bed, cross head guides on the bed between the cylinder at one end and the crank shaft at the opposite end, a valve actuating rock shaft journaled on the bed below the cylinder and cross head guides, a valve actuating rocker arm projecting upwardly from said rock shaft and an operating arm projecting laterally from said rock shaft away from the cylinder, a reversing shaft journaled on the bed plate in front of the rock shaft, a slotted reverse link mounted on the bed plate and between the rock shaft and reversing shaft with the concave side of the slot therein faced upwardly, an auxiliary crank fixed on the main crank, an auxiliary connecting rod engaged at one end with said auxiliary crank, a radius link having its lower end shiftably pivoted in the slot of the reverse link and carrying at its upper end a fulcrum for the auxiliary connecting rod, a connecting link suspended from the auxiliary connecting rod and having its upper end pivoted to the end of said connecting rod at a point beyond the fulcrum of said rod and its lower end pivotally engaged with the laterally extending arm of the rock shaft, an upwardly projecting arm on the reverse shaft, a reach link extending from said upwardly projecting arm over the reverse link and connected with the shiftable pivotal support for the lower end of the radius link and an operating lever extending 110 upwardly from said reverse shaft.

4. A steam engine of the horizontal type comprising engine bed, a cylinder mounted on the bed at one end, a crank shaft journaled at the opposite end of the bed, cross head guides on the bed between the cylinder at one end and the crank shaft at the opposite end, a valve actuating rock shaft journaled on the bed below the cylinder and cross head guides, a valve actuating rocker arm projecting upwardly from said rock shaft and an operating arm projecting laterally from said rock shaft away from the cylinder, a reversing shaft journaled on the bed plate in front of the rock shaft, a slotted reverse link mounted on the bed plate and between the rock shaft and reversing shaft with the concave side of the slot therein faced upwardly, an auxiliary crank fixed on the main crank, an auxiliary connecting rod engaged at one end with said auxiliary crank, a radius link having its lower end shiftably pivoted in the slot of the reverse link and carrying at its upper end a fulcrum for the auxiliary connecting rod, a connecting link suspended from the auxiliary connecting rod and having its upper end pivoted to the end of said connecting rod at a point beyond the fulcrum of said rod and its lower end pivotally engaged with the laterally extending arm of the rock shaft, an upwardly projecting arm on the reverse shaft, a reach link extending from said upwardly projecting arm over the reverse link and connected with the shiftable pivotal support for the lower end of the radius link and an operating lever extending 120 upwardly from said reverse shaft.

5. A steam engine of the horizontal type comprising engine bed, a cylinder mounted on the bed at one end, a crank shaft journaled at the opposite end of the bed, cross head guides on the bed between the cylinder at one end and the crank shaft at the opposite end, a valve actuating rock shaft journaled on the bed below the cylinder and cross head guides, a valve actuating rocker arm projecting upwardly from said rock shaft and an operating arm projecting laterally from said rock shaft away from the cylinder, a reversing shaft journaled on the bed plate in front of the rock shaft, a slotted reverse link mounted on the bed plate and between the rock shaft and reversing shaft with the concave side of the slot therein faced upwardly, an auxiliary crank fixed on the main crank, an auxiliary connecting rod engaged at one end with said auxiliary crank, a radius link having its lower end shiftably pivoted in the slot of the reverse link and carrying at its upper end a fulcrum for the auxiliary connecting rod, a connecting link suspended from the auxiliary connecting rod and having its upper end pivoted to the end of said connecting rod at a point beyond the fulcrum of said rod and its lower end pivotally engaged with the laterally extending arm of the rock shaft, an upwardly projecting arm on the reverse shaft, a reach link extending from said upwardly projecting arm over the reverse link and connected with the shiftable pivotal support for the lower end of the radius link and an operating lever extending 130 upwardly from said reverse shaft.

the laterally extending arm of the rock shaft, an upwardly projecting arm on the reverse shaft and a reach link extending from said upwardly projecting arm and connected with the shiftable pivotal support for the lower end of the radius link, the lower end of the radius link being forked to embrace the reverse link, the reach link being forked to embrace the fork of the radius link, the actuating arm being widely forked to receive the reverse link and the lower forked ends of both the radius link and reach link and the lower end of the connecting link being widely forked to span the reverse link and the forked ends of both the radius link and reach link. 15

In witness whereof, I have hereunto set my hand this 3rd day of November, 1925.

HU M. HARRIS.
